CLAIM

The ornamental design for a razor case, as shown and described.

DESCRIPTION

FIG. 1 is a first perspective view of a design of a razor case of the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is second perspective view thereof;

FIG. 9 is a first perspective view of a design of a second embodiment of a razor case of the present invention;

FIG. 10 is a front view thereof;

FIG. 11 is a back view thereof;

FIG. 12 is a right side view thereof;

FIG. 13 is a left side view thereof;

FIG. 14 is a top view thereof;

FIG. 15 is a bottom view thereof; and,

FIG. 16 is a second perspective view thereof.

The broken lines illustrate portions of the razor case and form no part of the claimed design.

1 Claim, 14 Drawing Sheets
